Filed Aug. 10, 1964, Ser. No. 388,547
5 Claims. (Cl. 49—192)

This invention relates to gates and is mainly, though not exclusively, concerned with a gate suitable for use when handling sheep and cattle.

According to the invention there is provided the combination of a rotatable gate post and a gate which is slidably endwise relative to the post.

The invention will be described in detail with reference to the accompanying drawings in which:

FIGURE 1 is a front elevation of a gate for use in handling livestock, and

FIGURE 2 is a view, on an enlarged scale, of a detail of the construction shown in FIG. 1.

As shown, a fixed vertical gate post 1 carries a bearing 2 for the upper journal portion 3 of a rotatable vertical post 4, the lower journal portion 5 of which is received in a bearing socket 6 embedded in the ground. The post 4 carries upper and lower projecting pins 7 and 8 respectively, upon the upper one of which is rotatably mounted a roller 9 which in turn is engaged by an inwardly open corner bead 10 formed by deformation of the tubular metal frame of a gate 11. Gate 11 is composed of a series of horizontal bars 15 rigidly secured at opposite ends to vertical end bars 16. The uppermost horizontal bar 15 intersects the upper ends of vertical bars 16 in similar outwardly offset integral arcuate corner loops or beads 10 and 13. These beads are essentially formed by upward bends in the top bar 15 and outward bends in the end bars 16. In the position shown in the drawings gate 11 is supported on post 4 by a pivotal mount between bead 10 and roller 9 and the lower portion of the gate 11 abuts against the lower stop pin 8 on the post 4 and thus prevents the gate from swinging clockwise about the axis of the roller 9. The gate may then be swung about the axis of the post 4 in the normal way and its free end secured, in the closed position of the gate, to another fixed gate post (not shown) by any convenient means such as the latching member 12. By placing latch 12 in the opposite vertical bar 16, the gate 11 may be reversed end to end and hung with loop 13 embracing roller 9.

By raising the free end of the gate slightly it is possible to dislodge the corner bead 10 from the roller 9 and at the same time raise the lower left-hand corner of the gate, as looked at in the drawings, clear of the pin 8. The gate can then be slid endwise relatively to the post 4 with the undersurface of its top rail riding over the roller 9 until the corner bead 13 engages over the roller.

With the construction shown and described the gate is capable of pivotal and sliding movement into any one of a number of positions.

I claim:

1. A gate comprising a gate post mounted for rotation about a substantially vertical axis, a gate structure, means freely pivotally supporting one upper corner region of said gate structure on the upper end of said post for rocking about a generally horizontal axis, said means also providing for upward displacement of said pivoted region of the gate structure, and stop means on the lower end of said post abutted by the corner region of said pivoted gate structure immediately below said one upper corner region whereby said gate structure extends substantially horizontally from said post, said gate structure having an upper part providing a horizontal slide track, and said pivotal support of the gate structure on the post comprising an inwardly open bead partly formed by an upwardly

2

looped end of said track surrounding a pivot structure on the post, said pivot structure and stop means being so relatively located vertically that upon upward displacement of said pivoted region of the gate structure the lower corner region of the gate structure moves above said stop means and the gate structure may be slidably displaced on said post with said track moving over said pivot structure.

2. A gate comprising a gate post mounted for rotation about a substantially vertical axis, a gate structure, means freely pivotally supporting one upper corner region of said gate structure on the upper end of said post for rocking about a generally horizontal axis, stop means on the lower end of said post abutted by the corner region of said pivoted gate structure immediately below said one upper corner region whereby said gate structure extends substantially horizontally from said post, said gate structure comprising an upper horizontal bar connected at opposite ends to the tops of vertical end bars, with the connection at the pivoted end of the gate comprising an inwardly open offset arcuate integral loop, and a slide pivot roller on said post within said loop, said stop means being a pin on the post engaging the lower end of the adjacent vertical gate structure bar.

3. In the gate defined in claim 2, said gate structure being substantially identical at both ends of said upper horizontal bar whereby either end of the gate may be pivotally supported on the post.

4. In combination, a gate post mounted for rotation about a substantially vertical axis and provided with a gate-supporting member, a barred gate having substantially vertical end members, an upper bar of said gate being longitudinally slidable on said gate-supporting member and being formed with upwardly arcuate ends which integrally merge with outwardly arcuate upper ends of said substantially vertical end members of the gate to provide corner beads for engaging said gate-supporting member, whereby either end of the gate can be hung from said gate post, said gate being prevented from swinging about said gate-supporting member in either of its hung positions by a stop projecting from said gate post in the path of swinging movement of the lower end of the mounted gate.

5. In combination, a gate post mounted for rotation about a substantially vertical axis and provided with a gate-supporting member in the form of a roller rotatably mounted on a substantially horizontal axis on said gate post, a barred gate having substantially vertical end frame members, an upper bar of said gate being longitudinally slidable on said roller and being formed with upwardly bent ends which are integrally combined with outwardly bent upper ends of said substantially vertical end members of the gate to provide offset inwardly open corner beads for engaging said roller, whereby either end of the gate can be hung from said gate post, said gate being prevented from swinging about said roller in either of its hung positions by a stop projection on said gate post disposed in the path of swinging movement of the lower end of said gate.
